[57] **CLAIM**

The ornamental design for an automobile tire, as shown
and described.

DESCRIPTION

FIG. 1 is a front perspective view of an automobile tire
showing my new design, it being understood that the
tread design is repeated uniformly throughout the cir-
cumference of the tire and the opposite side is the same
as that shown;

FIG. 2 is a front elevational view thereof;

FIG. 3 is a rear elevational view thereof;

FIG. 4 is a side elevational view thereof; and,

FIG. 5 is an enlarged fragmentary front elevational
view thereof.

FIG. 1

FIG. 2

FIG. 3

FIG. 4

FIG. 5
